Fig. 2.

Fig. 1.

Fig. 3.

Fig. 4.

Fig. 5.

FIG. 1 is a top plan view of a water closet bowl showing my new design;

FIG. 2 is a left side elevational view thereof;

FIG. 3 is a right side elevational view thereof;

FIG. 4 is a front elevational view thereof; and

FIG. 5 is a cross sectional view taken on line 5-5 of FIG. 4.

This is a divisional of design application Ser. No. D. 20,960, filed Jan. 16, 1970, now abandoned.

The characteristic feature of my design resides in the graining striations in the front of the base of the water closet bowl that split and separate from each other and they extend downwardly and around opposite sides of the base towards the back of the water closet bowl.

I claim:

The ornamental design for a water closet bowl, as shown and described.
